METHOD FOR UNSTOPPING A CLOGGED PIPE

Martin Leiser, 723 Columbia S.,

Los Angeles, Calif. 90017

Filed Sept. 26, 1966, Ser. No. 581,900

3 Claims. (Cl. 134—24)

ABSTRACT OF THE DISCLOSURE

A method for unstopping a clogged pipe by inserting in the open end of said pipe, which is substantially filled with water, a porous, resilient material, which is adapted to engage the inner peripheral surface of the pipe, and moving the porous, resilient material back and forth within the pipe in short rapid strokes so as to create a pressure front within the pipe and relieve the stoppage. A device for unstopping a clogged pipe which comprises a porous, resilient head having top and bottom surfaces and an intercommunicating pore structure such that the porous resilient head becomes engorged with water on contact therewith, and a handle having an inner end and an outer end, the outer end being bent in the form of an open hook, the inner end comprising a pair of gripping prongs having relatively blunt ends, which gripping prongs are inwardly biased and extend into the porous head at a point intermediate its top and bottom surfaces.

This invention relates to a novel method for unstopping a clogged pipe. Further, this invention pertains to a drain cleaning device.

The common household sink is a frequent source of frustration to the average housewife. It can easily become stopped up and it is generally an awkward and time-consuming operation to relieve the stoppage. The inevitable plunger or pipe snake required to do the job will generally require a man's services. Until then, the sink remains clogged and, if inadvertently used, may result in a flooded bathroom or kitchen.

An object of the invention is to provide a method for unstopping a clogged pipe which does not involve the use of bulky equipment and can be readily practiced by the housewife.

A further object of the invention is to provide a simple yet effective, drain cleaning device which is of a generally small size and is therefore capable of use by the housewife.

Additional objects will become apparent from the description and claims which follow taken in conjunction with the accompanying drawing showing a preferred embodiment of the invention. In the drawings:

FIG. 1 is an exploded perspective view of the drain cleaner;

FIG. 2 is a vertical sectional view of the drain cleaner inserted in a drain pipe partially filled with water and showing the head of the drain cleaner in partial section; and

FIG. 3 is a transverse sectional view through the drain cleaner head and drain pipe taken along the lines 3—3 of FIG. 2.

Referring to FIG. 1 of the drawing, there is shown the component parts of the drain cleaner in exploded view. The drain cleaner comprises a porous resilient head 2 in which the pores are intercommunicating. Connected to the porous resilient head is a handle 4 which can be of any suitable shape. Preferably, however, the upper portion of handle 4 forms a hook or similar configuration as indicated at 5 in FIG. 2. This provides a convenient means for hanging my drain cleaning device, when not in use, as for example, by placing the hook 5 over the edge of a sink or by hanging it from the valve handle beneath

2

the sink. Although the porous resilient head is shown in FIG. 1 as being square, the head can be of any convenient shape so long as it is slightly larger than the drain pipe into which it is to be inserted.

Turning to FIG. 2, the drain cleaner of my invention is shown inserted within a drain pipe 6 connected to the bottom of a sink 12 or similar plumbing fixture. As shown, the pipe may be full of water to a water level as indicated at 8, or the sink 12 or similar plumbing fixture may be full of water due to the stoppage within drain pipe 6.

The lower end of the handle 4 forms a pair of gripping prongs 14 which are biased to an inward position by the configuration of the handle. The gripping prongs are embedded within the resilient head 2 at a point intermediate its extremities to grip it securely. This presents a soft surface 16 at the bottom portion of the head 2 when inserted within a drain pipe. Frequently drain pipes contain a cross member located in the pipe a relatively short distance, such as 6 inches, or so, from the opening of the drain. Such a cross member is not shown in the drawings. By having a soft bottom surface, as at 16, my drain cleaning device does not strike a cross member with any considerable force but rather the surface 16 cushions the contact between my drain cleaning device and a cross member.

In use, my drain cleaner is employed in the manner illustrated in FIG. 2. It is inserted within a drain pipe and is moved rapidly back and forth by means of the handle 4. By virtue of its size and resilient consistency, the head 2 asserts pressure on the inner peripheral surface of the pipe 6 and forms a seal therewith. Movement of the head 2 in a rapid reciprocating fashion using a relatively short stroke, such as, for example, 1 and $\frac{1}{2}$ to 2 inches, creates a pumping action within the pipe as indicated by reference numeral 10 which refers to the series of pressure waves created within the fluid contained in the pipe.

The intercommunicating porous structure of the head 2 allows liquid to permeate throughout the porous head when the head is contacted with the liquid. In its engorged state, i.e., filled with water, the head 2 presses very firmly against the inner peripheral surface of the drain pipe 6. This is shown in transverse section in FIG. 3. However, by virtue of its intercommunicating pore structure, the head 2 can actually move through the liquid standing in the pipe, as shown in FIG. 2. As the liquid moves through the porous head 2, it, of course, encounters considerable resistance due to the friction offered by the fine pores within the head. However, this passage of liquid, small though it is, is believed to assist the seal between the inner peripheral surface of the drain pipe 6 and the porous head 2, which in turn enhances the pumping action caused by the rapid reciprocatory movement of the head within the drain pipe.

As described, my invention provides a novel pipe cleaning device and a novel method employing its use in unstopping clogged drain pipes. Although exemplified by reference to a specific embodiment, it should be understood that this embodiment is used only for purposes of illustration and should not be construed as limiting my invention. In operation, I have found that 10 or so rapid reciprocating strokes of my cleaning device is sufficient to force the clogging material from the sink trap, thus alleviating the stoppage and allowing free flow of liquid. The average pore diameter of the intercommunicating pores within the porous resilient head of my device may be varied within the scope of the invention. By way of illustration, I have found an average pore diameter of $\frac{1}{16}$ to $\frac{3}{32}$ inch to be satisfactory. The resiliency of the material comprising the porous head 2 can likewise be

varied within the scope of my invention, so long as the head affords sufficient resiliency to bear tightly against the inner peripheral surface of the drain pipe. Various natural and synthetic materials may be employed in forming the porous resilient head of my cleaning device. For example, the head may be composed of polyurethane foam.

My device and method are both characterized by their simplicity and effectiveness. Due to its simplicity, my device can be readily manufactured in a large volume at a low unit cost.

Although I have demonstrated my invention with regard to alleviating stoppages in drain pipes, the phenomenal pumping action afforded by the resilient head of my cleaning device with its intercommunicating pore structure, may have other applications. To illustrate, this pumping action could be employed in a piston type pump in which the piston would be formed of a porous resilient material having an intercommunicating pore structure. On movement of such a piston within a cylinder, the piston would act to pump liquid against a pressure head.

Having fully defined my invention by reference to the foregoing specification and drawing, I desire to be limited only by the lawful scope of the appended claims.

I claim:

1. Method for unstopping a clogged pipe, said method comprising inserting in the open end of said pipe which is substantially filled with water a porous resilient material which is adapted to engage the inner peripheral surface of said pipe, said material having an intercommunicating porous structure such that said material becomes engorged with water on insertion into said pipe, whereby the seal between said material and the inner

peripheral surface of said pipe is optimized due to the volume of water contained within said material, and moving said porous, resilient material back and forth within said pipe in short rapid strokes so as to create a pressure front within said pipe and thereby unstop it.

2. The method of claim 1 wherein a handle is connected to said porous resilient material, said handle extending into and engaging said resilient material at a point intermediate its length such that the inner end of said material is soft and resilient, said handle being used to move said porous resilient material back and forth within said pipe while presenting said soft resilient inner end to cross members within said pipe.

3. The method of claim 1 wherein the pores within said porous resilient material have an average pore diameter ranging from about $\frac{1}{16}$ to about $\frac{3}{32}$ of an inch.
